(57) **CLAIM**

What is claimed is the ornamental design for a transparent plant tag, as shown and described.

DESCRIPTION

FIG. 1 is a perspective view of the transparent plant tag of the present invention;

FIG. 2 is a front view thereof;

FIG. 3 is a rear view thereof;

FIG. 4 is a top view thereof;

FIG. 5 is a bottom view thereof;

FIG. 6 is a side view thereof, the opposite side view being a mirror image thereof; and,

FIG. 7 is a front view of the transparent plant tag of the present invention positioned in a potted plant.

The broken indicia and broken lines in the drawing are for illustrative purposes only and form no part of the claimed design.
